UNITED STATES PATENT OFFICE.

ALBERT WEBER, OF CLEVELAND, OHIO.

SIFTER.

1,081,919.

Specification of Letters Patent. Patented Dec. 16, 1913.

Application filed May 5, 1913. Serial No. 765,520.

To all whom it may concern:

Be it known that I, ALBERT WEBER, citizen of the United States, residing at Cleveland, in the county of Cuyahoga and State 5 of Ohio, have invented certain new and useful Improvements in Sifters, of which the following is a specification.

This invention relates to sifters and screens adapted particularly for household 10 use, but capable of use in foundries for sifting core powder or the like, or for use in any circumstances requiring powdered material to be sifted or distributed.

The object of the invention is to provide 15 a simple easily operated device of the kind, which can be cheaply made, and which can be operated by one hand.

The invention is illustrated in the accompanying drawings in which—

20 Figure 1 is a side elevation of the sifter. Fig. 2 is a top plan view thereof.

Referring specifically to the drawings 6 indicates a cylindrical vessel or container 25 for the material to be sifted, and this has a screen 10 at the bottom. A ring 8, conveniently made of wire, extends around the vessel near the bottom thereof, and is spaced therefrom. This ring is extended at one side as indicated at 9 to form a handle, and 30 at diametrically opposite points it has uprights 7 which are turned in at the top to form pivots projecting into the wall of the vessel 6 near the top thereof. The vessel 6 is thus hung or suspended between the piv-

ots so that it will swing or oscillate within 35 the ring 8, to agitate the material in the vessel and thus sift the same. By grasping the handle 9 and shaking the article back and forth the vessel is caused to oscillate and at each oscillation the lower end thereof raps 40 against the ring, swinging back and forth from one side of the ring to the other, and the raps jar the contents of the vessel and so sift and distribute the same through the screen. The vessel can be easily removed for 45 cleaning or other purposes by springing the uprights 7 apart.

The simplicity of the device is obvious. It is illustrated as a household sifter; but it may be constructed of any size or material 50 and thus adapt it for foundry or other uses.

What I claim as new is:

A sifter comprising a frame adapted to be shaken, and having uprights at opposite sides thereof, a vessel, having a sifting 55 screen bottom, pivoted near its top to said uprights and depending at its lower end between opposite sides of the frame to oscillate in a vertical plane between and rap against opposite sides of the frame when the latter 60 is shaken.

In testimony whereof, I do affix my signature in presence of two witnesses.

ALBERT WEBER.
